UNITED STATES PATENT OFFICE.

ADRA M. HUBBARD, OF DALLAS, TEXAS.

STEAM GENERATOR.

Application filed October 30, 1924. Serial No. 746,860.

This invention relates to steam generators, and more particularly to steam generators of the flash type, the primary object of the invention being to provide means for controlling the condition of the steam at all times to insure a dry steam entering the cylinders of an engine receiving steam from the generator.

Another important object of the invention is to provide means for controlling the quantity of water entering the generator coil to prevent unnecessary cooling of the coils to decrease the efficiency of the generator.

A still further object of the invention is the provision of means supported between sections of the coils to break up the water passing therethrough to insure against vacuum blocks in the coils.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a diagrammatic view disclosing the coils and controlling means of a generator constructed in accordance with the invention.

Figure 2 is a transverse sectional view through the coils.

Figure 3 is a vertical sectional view through the coils.

Figure 4 is a longitudinal sectional view of the atomizer disposed between the coils for breaking up the water passing therethrough.

Referring to the drawing in detail, the reference character 5 designates the water tank that supplies the necessary water to the generator, and as shown, the water tank 5 is in communication with the pump 6 through the pipe 7. The pump 6 is of the usual construction and has connection with an operating rod 8, which in turn is connected with a suitable operating mechanism not shown.

Pipes 9 establish communication between the pump 6 and pipe 10 that is connected with the pipe 11 formed with a curved lower extremity 12 which has connection with the valve housing 13. A return pipe 14 connects the valve housing 13 with tank 5 so

that when the water in the system is cool, and the coils of the system are filled, water may be returned from the valve housing to the tank 5 and not carried through the system until the coils of the system are sufficiently hot.

The upper end of the pipe 11 extends laterally as at 12' from where it extends downwardly and connects with the vertical pipe 13', by means of the union 14', there being provided a check valve 15 in the pipe 12' to prevent water from returning through the pipe 12' to the pump.

This pipe 13' extends downwardly as clearly shown by Figure 1 of the drawing and communicates with the feed water coil 16 of the system, which is spirally formed. The pipe 17 forms a continuation of the feed water coil 16 and is shown as entering the head 18 in which the expansion tube 19 is positioned, the upper end of the expansion tube being secured within the head 20 of the thermostat to be hereinafter more fully described.

The heads 18 and 20 have lateral extensions 21 to which the rods 22 are connected so that the heads will move with the rods, the lower ends of the rods 22 extending through the lateral extensions 23 of the valve casing, where they support coiled springs 24 so that movement of the tube 19 will be compensated for.

Carried by the head 18 is a rod 25 which has a ball valve 26 secured to its lower end, which ball valve is adapted to seat at 27 to cut off the passage of liquid through the tube 12 and is adapted to seat at 28 to allow water to pass into the valve casing upon contraction of the tube 19.

The main coils of the system are indicated at 29 and 30 respectively, the coil 29 being an outer coil, while the coil 30 is an inner coil, the tubes of the coil 30 being disposed directly above the spaces between the tubes of the coil 29 so that heat passing upwardly between the tubes of the coils will contact with all of the tubes of the coils to efficiently heat the water contained therein.

Goose necks 31 are formed at the ends of certain coils, which goose necks are connected by the casing 32 of an atomizer, to be hereinafter more fully described, so that water passing from one coil to the other will be broken up into fine particles to insure a dry steam.

The atomizer is formed with a contracted portion 33 which merges into an enlarged portion 34 in which the nozzle 35 is positioned, the nozzle 35 being inverted cone-shaped and formed with a plurality of openings 36 through which the water must pass on its passage through the bottom of the atomizer.

It might be stated that it has been found 10 in practice that water in coils of a generating system of the type as shown and described, will fill the upper portions of the coil and will generate steam at a certain point in the tubes at which point the atomizer as 15 described is positioned, so that the water will be broken into a fine spray, to the end that a dry steam will be provided at all times.

It is to be understood that a suitable flame 20 or heat producing medium will be disposed adjacent to the coils to heat the tubes of the coils for generating steam.

At the lower end of the coils is a pipe 37 which forms a continuation of the coil 25 30 so that the steam may be carried off to engine cylinders, for the operation thereof.

In the operation of the device, the pump is actuated to supply the necessary water 30 to the pipe 13' from where it passes to the coil 16 and is heated, the heated water passing to the tube 19 which expands, forcing the ball valve to the seat 27 causing water to pass through the pipe 12', coil 16, pipe 17 and into the coils 29 and 30, where it is converted into steam and carried off through pipe 37 to the cylinders of the engine operated thereby.

Should the supply of water become excessive and tend to cool the water in the 40 pipes, it is obvious that the water which is not converted into steam and which passes through tube 19, will act to cool the tube causing the valve member 26 to move from its seat 27 to the end that the water forced 45 into the system by the pump 6 will pass through pipe 11 and be returned to the tank 5 through the pipe 14.

When the supply of water in the tubes is decreased to a certain degree, the heat 50 will cause the tube 19 to again expand and seat the valve 26 to the end that the water will pass through the pipe 12' and into the feed water coil and generator coils as described.

55 It might be further stated that due to the

construction of the atomizer, the atomizer will automatically control the booster nozzle of the atomizer and compensate for water drawing on the generator at all pressures, because the water passing through the atomizer is broken into a fine spray before it enters the inner coil of the system insuring a dry steam.

I claim:

1. A steam generator including generator 65 coils and a feed water coil, a source of water supply, a pipe establishing communication between the source of water supply and feed water coil, a thermo-responsive tube establishing communication between the feed 70 water coil and the generator coils whereby water may flow from the feed water coil to the generator coils, and a valve operated by the thermo-responsive tube for controlling the passage of water from the source of 75 water supply to the feed water coil.

2. A steam generator including generator coils and a feed water coil, a feed water tank, a feed pipe through which water passes from the tank to the feed water coil, 80 a return pipe connected with the feed pipe and tank, a valve in the return pipe to control the passage of water to the feed water coil or to the tank, an expansion tube establishing communication between the feed water coil and the generator coils, and through 85 which heated water passes to the generator coils, and a rod connected with the expansion tube to move therewith and operate the valve.

90 3. A steam generator including generator coils and a feed water coil, a feed tank, pipes establishing communication between the feed water coil and feed tank, an expansion tube, a pipe establishing communication between the feed water coil and the expansion tube, a pipe establishing communication between the generator coils and expansion tube, a valve for controlling the passage of water from the feed tank to the 100 feed water coil, and a rod connected with the expansion tube to move therewith, said valve being movable by the action of the rod to control the passage of water to the valve by the heat of the water passing into the expansion tube.

In testimony that I claim the foregoing as my own, I have hereto affixed by signature.

ADRA M. HUBBARD.
